DESIGN FOR A TIE CLASP

Henry De Ambrogio, San Francisco, Calif.

Application April 17, 1945, Serial No. 119,055

Term of patent 14 years

(Cl. D17—10)

To all whom it may concern:

Be it known that I, Henry De Ambrogio, a citizen of the United States of America, residing in the city and county of San Francisco and State of California, have invented a new, original, and ornamental Design for a Tie Clasp, of which the following is a specification, reference being had to the accompanying drawing, forming part thereof.

I claim:

The ornamental design for a tie clasp, as shown.

HENRY DE AMBROGIO.
